United States Patent

Des. 240,990
Patented Aug. 17, 1976

240,990

HANGER

Bruce Bernstein, New York, N.Y., assignor to Handiform
Plastic Corp., New York, N.Y.

Filed Jan. 3, 1975, Ser. No. 538,445

Term of patent 3½ years

Int. Cl. D6—08

U.S. Cl. D6—248

FIG. 3

FIG. 1

FIG. 2

FIG. 4

FIG. 1 is a front elevational view of a hanger showing my new design;

FIG. 2 is a side elevational view taken from the right of FIG. 1;

FIG. 3 is a side elevational view taken from the left of FIG. 1; and

FIG. 4 is a bottom plan view thereof.

I claim:

The ornamental design for a hanger, substantially as shown.
